ABSTRACT: A knockdown or demountable boltless table in which the legs are formed in pairs, the legs of each pair being formed as a rigid unit. The pairs of legs are connected together, by easily connectable and disconnectable side rails, to form a rigid table structure, free of wobble, or dismantled.

KNOCK-DOWN DRAFTING TABLE

BACKGROUND OF INVENTION

Knockdown tables are in common use where it is desired to ship the table in a dismantled condition, for moving from one location to another and other reasons. An important feature of such structures is that they must be easy to assemble and of course, rigid and wobble free when used. The knockdown structures presently in use do not provide such tables.

DESCRIPTION OF INVENTION

The invention herein described provides a boltless knockdown or demountable type of table construction that overcomes the disadvantage of the prior art structures and also provides a table which utilizes rail and leg connectors that can be easily assembled and dismantled without the use of tools. The invention provides a simple knockdown structure which, when assembled, is at the same time sufficiently stable, rigid and accurately assemblable to be useful for applications where rigidity is an essential requirement. It also provides a simple rigid rail-to-post connection that is adapted to mass production application in the metal frame furniture industry particularly in conjunction with readily available extruded or rolled metal cross members.

The boltless knockdown table herein disclosed consists of two pairs of legs, each pair of legs comprising tubular upright members in spaced apart relation rigidly connected together by cross members, a pair of horizontal rails forming side members of the table, each rail having at each end a connector consisting of downwardly projecting teeth, a complementary connector bracket mounted on the side of the upright member each contiguous to the top end thereof and facing inwardly thereof, slots in each bracket positioned to register with its respective tooth, said teeth having a tapered edge which engages against an opposing slot edge of said bracket to thereby draw the ends of the rails tightly against the brackets when the teeth are forced into locking engagement with the respective brackets to thereby form a rigid unitary structure free of wobble.

The above and other objects of the invention will become apparent from the following description and drawings. In the drawings:

FIG. 1 is a perspective view of an assembled complete table unit embodying the invention;

FIG. 2 is a fragmentary view of one corner of a table rail and leg showing the front connector construction;

FIG. 3 is a top view of a corner of a table unit embodying the invention with a locking device;

FIG. 4 is a section on the line 4-4 of FIG. 3;

FIG. 5 is a section on the line 5-5 of FIG. 4;

FIG. 6 is a detailed view of the removable drawer guide; and

FIG. 7 is a fragmentary exploded view of the back horizontal rail and connector construction.

The boltless knockdown table unit, as best shown in FIG. 1, comprises two pairs of legs 8, 9, each pair comprising spaced apart upright members 10, 10a connected into a rigid unit by lower and upper cross members 6, 7. The connection between the cross members and the uprights is preferably accomplished by welding. The upright members are of tubular form (preferably made of mild steel) and preferably square in cross section.

The two pairs of legs, 8, 9 are connected together by detachable longitudinal horizontal front and back rails 11, 11a which will be more particularly described.

Each end of each horizontal rail 11 is connected to its respective upright member 10a by the same means. Consequently, only one end of the connection will be described. By way of illustration, each end of horizontal rail 11 is detachably connected to its respective upright member by connectors generally as shown in FIG. 2 and detailed in FIGS. 3, 4 and 5.

Each upright of each of legs 10a is provided with a bracket 14 preferably of U-shaped, the bracket being welded to the inside vertical face of the upright member contiguous to the top end thereof.

5 The horizontal rail 11, in the present illustration, is formed as a hollow member of C-form, in cross section, one wall of the rail being bent to form the flange 12. Each end of each rail has inserted and secured therein a carrier 17, the carrier being provided with outwardly and downwardly projecting teeth 18, 19.

10 The upper crossmembers 7 in the present illustration are made the same as the rails 11 and have one of their walls bent to form a flange 12a complementary to the flange 12 so that when assembled the flange 12 which supports the table top 13 extends completely around the inside wall of the assembled rails and cross members.

15 Each bracket 14 in the present illustration has two slots 15, 16 disposed vertically, one above the other to receive the two notched teeth 18, 19. Each notched tooth has a tapered gripping edge 20 arranged so that when the teeth 18, 19 have been inserted in the slots 15, 16 and the horizontal rails 11, 11a are lowered into place the wedging action of the edge 20 against the edges of the slots 15, 16 pulls the rail ends into 20 rigid abutting relationship with the respective bracket 14. It will be seen that the upper slot 15 is opened upwardly and is somewhat shorter than the slot 16. The purpose of this is not only for ease in assembly but also makes for improved construction in aligning the top edge of the rails, the top edge of 25 the bracket and the top edge of the upright member.

30 There is also provided a means of locking the assembled connections by way of threaded pins 21 passing through the channel 14 in a position to engage the upper edge of the tooth 18, to thereby prevent the accidental upright movement of the 35 horizontal rail 11 which movement would dislodge the connection.

35 The back rail 11a, as will be seen from FIGS. 1 and 7, is slightly deeper than the front rail 11. The means for connecting each end of the back rail 11a to its respective post comprises a bracket 14a cut from U-shaped angle iron which has a series of modular slots 16a, only three of the four shown being used. The uppermost slot is a half-slot to simplify the construction. Each end of the rail 11a is provided with carrier 17a welded to the upright inside face of the rail 11a. The carrier 40 has three teeth, 18a, 19a and 20a similar to the teeth 18, 19. The two upper teeth are spaced to engage in the half slot and the adjacent full slot while the tooth 20a engages in the lowest slot of the slots 16a. A locking means similar to pin 21 is 45 also provided for the rear rail.

50 The right hand rail 7 is provided with a drawer guide 22 which is welded to the side and a drawer guide 23 carrier between the front rail 11 and the back rail 12. The mounting for the rail 11 comprises a U-bracket 24 welded to the inside 55 face of the rail 11 and an oppositely disposed similar U-bracket (not shown) mounted on the inside face of the front rail 11. A removable drawer 25 is supported on the rails 22, 23.

55 The assembly of the boltless table will now be described. To 60 assemble the structure as shown in FIG. 1, the first step, of course, is to place the two pairs of legs 8, 9 in an upright position. The back rail 11 is then brought into position and the teeth on the carrier 17a are entered in the respective slots and then tapped lightly to drive the teeth into secure engagement.

65 The same step is followed to attach the front rail 11. The removable rail 23 is then mounted in position so that it will be supported by the bracket 24 on the rear rail and a similar bracket carried on the front rail. The locking means is then 70 screwed into position.

To dismantle the table the reverse procedure is followed.

75 While one embodiment of the invention has been shown and described in detail it will be understood that this is illustrative only and is not to be taken as a definition of the scope of the invention.

I claim:

1. A boltless knockdown table consisting of two pairs of legs, each pair of legs comprising:
  - a. a pair of tubular upright members in spaced apart relationship rigidly connected together by crossmembers; said upright members being of rectangular cross section;
  - b. a pair of detachable rigid horizontal side rails forming the side members of the table;
  - c. each crossmember and each horizontal side rail being substantially flat and having upper and lower inwardly projecting flanges, the upper flange terminating in an inwardly facing recessed L-flange to form a longitudinal top supporting flange;
  - d. each rail having at each end downwardly and outwardly projecting teeth;
  - e. a complementary U-shaped connector bracket mounted on the inside of each upright member adjacent the top end thereof;
  - f. teeth receiving apertures in each bracket, the uppermost aperture being in the form of an open slot terminating at the top edge of the bracket; and
  - g. a pair of parallel and coplanar drawer guides, one of said pair of guides being permanently secured to one of the crossmembers of said table and the other of said guides having its opposite ends removably supported by the front and back rail respectively, said support comprising a pair of U-brackets one of which is secured to the inside face of the front rail and the other secured to the inside face of the back rail whereby the legs and rail members are

quickly assembled with each rail end held tightly against its respective bracket to thereby form a rigid, wobble free table and dismantled therefrom.

2. A boltless knockdown table consisting of two pairs of legs, each pair of legs comprising:
  - a. a pair of tubular upright members in spaced apart relationship rigidly connected together by crossmembers;
  - b. a pair of detachable horizontal side rails forming the side members of the table;
  - c. each rail having at each end downwardly and outwardly projecting teeth and an abutment which abuts against an upright face of its respective upright member;
  - d. a complementary connector bracket mounted on the inside of the upright members adjacent the top end thereof;
  - e. teeth receiving slots in each bracket and a releasable locking members consisting of a setscrew carried by each bracket, entered through the bracket in a position to engage between said teeth to thereby prevent inadvertent dislodgement of the teeth from the bracket; and
  - f. a pair of parallel and coplanar drawer guides, one of said pair of guides being permanently secured to one of the crossmembers of said table and the other said guides having its opposite ends removably supported by the front and back rail respectively, said support comprising a pair of U-brackets one of which is secured to the inside face of the front rail and the other secured to the inside face of the back rail.
